CHARCOAL BURNER

St. Clair C. Holland, Montreal, Quebec, Canada

Application June 9, 1937, Serial No. 147,331
In Canada December 10, 1936

6 Claims. (Cl. 126—73)

This invention relates to improvements in charcoal burners used in connection with railway cars to prevent freezing of fruits, vegetables and other perishable products.

More particularly, the invention comprises a generally improved and simplified burner construction in which a single damper is provided in conjunction with a ventilator to control both the inflow of combustion supporting air and the outflow of combustion gases. In the present instance the invention is shown embodied in a burner which is adapted to be mounted beneath the floor of a car and is equipped with a water heating coil adapted to be connected in circuit with the circulating pipes of a hot water heating system located within the car.

According to this invention a single damper is mounted at the front of the burner so that its upper portion controls the outer end of the smoke flue leading from the fire pot while its lower portion controls the outer end of an air inflow passage through which combustion supporting air is supplied to the ash pit below the grate on which the charcoal or other fuel is burned. A ventilator is arranged over the upper portion of the damper and is designed so that, when the car is in motion, the resulting flow of air through the ventilator tends to set up a suction in the smoke flue which assists in drawing out the smoke and products of combustion.

Proceeding now to a more detailed description reference will be had to the accompanying drawings, in which—

Fig. 1 is a fragmentary front elevation of a charcoal burner constructed in accordance with this invention.

Fig. 2 is a fragmentary transverse sectional view taken substantially along the line 2—2 of Fig. 1.

Fig. 3 is a front plan view of the base or stationary element of the damper.

Fig. 4 is a front elevation of the movable element of the damper.

Fig. 5 is an enlarged vertical sectional view of the complete damper assembly.

Fig. 6 is a top plan view of the ventilator which is used in conjunction with the damper.

Fig. 7 is a front elevation of the ventilator.

Fig. 8 is an end elevation of the ventilator.

In the present instance I have shown the burner provided with an outer casing 5 of rectangular configuration but this is not essential since the casing may be cylindrical or other suitable shape. A fuel hopper 6 of substantially inverted frusto-conical shape is supported in the

upper portion of the casing by suitable supporting brackets 7. The lower portion of hopper 6 is seated in the flaring mouth 8 of a cast metal fire pot 9 provided with a suitable grate 10, the latter being spaced above the bottom 11 of the fire pot to provide the ash pit 13. The hopper 6 is provided with a charging opening 14 directly opposite a similar opening 15 in the front wall 5a of the casing 5, said opening 15 being normally closed by a suitable charging door 16. The openings 14 and 15 are connected by a sheet metal flue member 18 through which the fuel is introduced into the hopper 6.

A smoke and gas outlet flue 19 is provided directly below the sheet metal flue 18. Flue 19 is bounded at the sides and bottom by a single sheet of metal bent into U-form to provide a bottom wall 20 and side walls 21, the upper edges of the latter being preferably secured to the bottom portion of the flue 18. The inner end of flue 19 communicates with the combustion chamber 22 through an opening 23 provided in the upper portion of the fire pot 9. Directly below the flue 19 there is provided a sheet metal air inflow flue 24 presenting an outer horizontal leg 25 and an inner vertical leg 26. The flues 19 and 24 are enclosed in the sense that there is no communication between them. Combustion supporting air passing inwardly through flue 24 is delivered to the ash pit 13 through one or more openings 27 in the lower portion of the fire pot.

The outer ends of the flues 19 and 24 are controlled by a single damper generally indicated at 29. This damper comprises a stationary base plate 30 and a movable damper element 31 provided with complementary openings 30a and 31a (compare Figs. 1, 3 and 4) adapted to be moved into and out of registry by rotation of the movable element 31.

The damper plate 30 is bolted, riveted, or otherwise secured to the front wall 5a of the burner casing 5 over a single large opening 32 which communicates with the outer ends of the flues 19 and 24. The movable damper element 31 (Figs. 2 and 5) is secured to the base plate 30 by a central pivot bolt 33 and is held in close contact with the base plate by a suitable spring 34 surrounding said bolt. This spring is seated in a recess 35 formed in the outer face of the damper element 31 and is confined in compression between the bottom wall of the recess and a washer 36 which is held in place by the nuts 37.

A ventilator, generally indicated at 39, is secured to the wall 5a of the burner casing 5 so as to overlie the upper half of the damper assembly.

28. This ventilator comprises a sheet metal structure presenting a front wall 40 which is spaced from the casing wall 5a by top and bottom walls 41 and 42. At its opposite ends the ventilator is provided with attaching flanges 43 which are bolted, riveted or otherwise secured to the casing wall 5a. Deflectors 44 are secured in place between the top and bottom walls of the ventilator so that air entering the ventilator at either 5 end is deflected outwardly through a front opening 45 provided in the front wall 40. At each 10 side of the opening 45 the front wall of the ventilator is preferably curved, as indicated at 47 in Fig. 6. The bottom wall of the deflector is also 15 preferably curved upwardly between its ends, as shown in Fig. 7. By comparing Figs. 6 and 8 it will be seen that the particular curvature of the front and bottom walls of the ventilator serves, in conjunction with the deflectors 44, to gradually 20 restrict the air inflow passages at the opposite ends of the ventilator so that the cross sectional area of each passage gradually diminishes as it approaches the front openings 45. By this construction air entering either end 25 of the ventilator is caused to travel with gradually increasing velocity toward and through the front opening 45.

The ventilator 39 is left open at both ends so that air will pass therethrough from either end 30 dependent upon the direction of travel of the car in which the ventilator is installed. When the damper 29 is open the air which enters one end of the ventilator 39 and is deflected outwardly through the front opening 45 creates a suction 35 in the flue 19 (Fig. 2) which assists in drawing out the gases and products of combustion from the fire pot 22, said gases and products of combustion being discharged through the flue 19 and through the damper openings 30b and 31b 40 to the ventilator 39, from whence they pass through the front opening 45. At the same time combustion supporting air enters the air inflow flue 24 through the lower damper openings 31b and 30b and passes downwardly through the vertical leg 26 of the flue 24 to the air inlet opening 27 of the fire pot. A guard plate 49a is preferably suspended from the ventilator 39 to overlie 45 the lower half of the damper assembly 29.

When it is desired to operate the burner under 50 maximum draft conditions the movable damper plate element 31 is turned to bring its openings 31b in full registration with the openings 30b of the stationary damper plate 30. When it is desired to regulate or retard the progress of combustion 55 the movable damper element 31 is rotated so that the solid portions separating the openings 31b are positioned to partially cover or throttle the openings 30b to the desired extent. When the damper element 31 is turned so that it 60 completely closes the openings 30b in the stationary damper plate 30 the inflow of combustion supporting air and the outflow of gases are both completely arrested so that the fire in the burner will be caused to die out in short order.

65 The movable damper element 31 is operated, through the agency of an axially movable operating rod 49 which, in turn, is shifted axially in either direction by screw-threaded engagement with a hand wheel 50 confined between suitable 70 brackets 51. Adjacent the end remote from the hand wheel 50, the rod 49 is provided with a pin 52 engaged in a slot 53 formed in a lug extension 54 of the damper element 31. It is also preferred to provide indicating means to facilitate positioning 75 of the damper in a definite heat control posi-

tion. To this end the rod 49 is provided with a pointer 55 cooperating with suitable markings 56 on a stationary scale 56a fastened to the front wall 5a of the burner casing.

The burner described herein is mounted beneath the floor of a refrigerator car and is equipped with a hot water heating coil 59 adapted to be connected to the circulating pipes of a hot water heating system located within the car. The connections between the coil and the 10 circulating pipes of the heating system may be made as shown in U. S. Patent 2,076,961 to C. D. Niven, dated April 13, 1937, or in any other suitable manner.

Having thus described my invention, what I 15 claim is:

1. A burner of the character described comprising a casing having a fuel magazine in the upper portion thereof, a fire pot arranged in the lower portion of the casing to receive fuel from said magazine, a horizontal smoke flue extending outwardly from a lateral opening in the upper wall portion of the fire pot to the front of said casing, an air admission flue including an outer horizontal portion positioned directly below the smoke flue and an inner vertical portion extending downwardly from the inner ends of the horizontal portion to deliver air toward the ash pit of the fire pot, a single rotary damper mounted at the front of the casing to control the 30 outflow of combustion supporting air through the air flue, a ventilator casing secured to the burner casing so as to overlie the upper half of the damper, said ventilator comprising a casing which is open at both ends and is provided with 35 a further opening in its front wall located directly in front of the upper portion of the damper, deflectors arranged in the ventilator casing so that air entering either end of said casing is directed toward the front opening and 40 a baffle plate depending from the bottom wall of the ventilator casing in spaced relation to the lower half of the damper.

2. A burner comprising a casing having a fuel magazine in the upper portion thereof, a firepot 45 arranged in the lower portion of the casing to receive fuel from the magazine, a grate in the lower portion of said firepot, an enclosed flue arranged to conduct products of combustion from the upper portion of said firepot to an opening in 50 said casing, an enclosed air inlet flue arranged to conduct combustion supporting air from a second opening in said casing to a space below said grate, a single damper controlling both of said openings, and an aspirator comprising a hood 55 secured to said casing, said hood being open at both ends, having an aperture aligned with the first mentioned opening in said casing and an opening in said hood opposite said aperture, said hood being formed so that air entering either of 60 said ends flows through said last mentioned opening and ejects therewith gases from said first mentioned flue.

3. A burner comprising a casing having a fuel magazine in the upper portion thereof, a firepot 65 arranged in the lower portion of the casing to receive fuel from the magazine, a grate in the lower portion of said firepot, an enclosed flue arranged to conduct products of combustion from the upper portion of said firepot to an opening 70 in said casing, an enclosed air inlet flue arranged to conduct combustion supporting air from a second opening in said casing to a space below said grate, a single damper controlling both of said openings, and a ventilator utilizing air 75

movements exterior of said burner to eject said products of combustion from the first mentioned opening in said casing, the wall of the casing having said second opening therein being substantially parallel to said air movements.

4. A burner comprising a casing having a fuel magazine in the upper portion thereof, a firepot arranged in the lower portion of the casing to receive fuel from the magazine, a grate in the lower portion of said firepot, an enclosed flue arranged to conduct products of combustion from the upper portion of said firepot to an opening in said casing, an enclosed air inlet flue arranged to conduct combustion supporting air from a second opening in said casing to a space below said grate, a single damper controlling both of said openings, and means to eject said products of combustion from the first mentioned opening in said casing, said means comprising a hood arranged to direct air moving exterior of said heater adjacent said first mentioned opening, thereby ejecting said products of combustion.

5. A burner having a fuel magazine in the upper portion thereof, a firepot arranged in the lower portion thereof to receive fuel from the magazine, a grate in the lower portion of said firepot, a flue arranged to conduct products of combustion from the upper portion of said firepot to the exterior of said burner, an air inlet flue arranged to conduct combustion supporting air from exterior of said burner to a space below said grate, a single damper controlling the exterior ends of both of said flues and a ventilator utilizing air movements exterior of said burner to eject said products of combustion from said

first mentioned flue, said air inlet flue being substantially normal to said air movements.

6. A burner comprising an outer casing provided with upper and lower damper openings, a fuel magazine mounted in the upper portion of the casing, a firepot arranged in the lower portion of the casing to receive fuel from the magazine, the circumferential wall of the fire pot being spaced from the surrounding wall of the casing and provided with upper and lower openings extending therethrough, the upper opening constituting an outlet for products of combustion and the lower opening serving as an air inlet passage placing the ash pit of the firepot in communication with the surrounding space enclosed by the casing, a flue forming an enclosed passage through which products of combustion are conducted from the upper opening of the firepot to the upper damper opening of the casing, a second flue forming an enclosed passage through which combustion supporting air is conducted from the lower damper opening of the casing to said space enclosed by the casing, a single damper arranged over the upper and lower damper openings of the casing to control the flow through both of said flues, and an aspirator comprising a hood secured to said casing, said hood being open at both ends, having an aperture aligned with the upper opening in said casing and an opening in said hood opposite said aperture, said hood being formed so that air entering either of said ends flows through said last mentioned opening and ejects therewith gases from said first mentioned flue.

ST. CLAIR C. HOLLAND.
